UNITED STATES PATENT OFFICE.

JACOB GREENBERG AND SAMUEL GOODMAN, OF CHICAGO, ILLINOIS.

CHILD'S GARMENT.

Application filed May 23, 1923. Serial No. 640,957.

The present invention relates to wearing apparel and particularly to baby garments.

The objects of the invention are to provide an improved garment for babies having 5 means for the storage of article of apparel and toilet; and also having means for the better protection of the child against exposure to the cold.

These, and such other objects as may hereinafter appear are obtained by the novel construction, combination and arrangement of the several parts of our invention which is fully illustrated in the accompanying single sheet of drawing made a part of this specification and in which:

Figure 1 is an elevation showing the garment buttoned for use, with one cuff extended and the other folded back;

Figure 2 is a fragmentary elevation of 20 the bottom of the garment showing the flap of the garment in open or extended position;

Figure 3 is an enlarged vertical section through the bottom portion of the garment; 25 and

Figure 4 is a plan view of the lining pattern employed upon said flap.

Like reference characters are used to designate similar parts in the drawing and in 30 the specification which follows.

Reference will first be had to Figures 1, 2 and 5. The garment illustrated comprises a back 10 having an extension or flap 11 with converging sides depending therefrom, 35 and either formed integrally therewith or stitched thereto (preferably the latter), and a front of right and left hand members 12 and 13 adapted to button one to the other and stitched at their sides and bottoms to 40 the back 10. A hood 14, cut from any suitable pattern and secured to back 10 and to front sections 12 and 13, may be made a part of the garment.

Flap 11 is faced on the inside with a sheet 45 15 of waterproof material, best shown in Figure 6, which sheet is folded at 16 and stitched adjacent thereto to provide a long pocket, such pocket being divided into two smaller sections or pockets 17 and 18, by stitching 19 through the two layers of waterproof material. Two half circular exten-

sions of sheet 15 provide flaps 20 to close pockets 17 and 18. Suitable hems are provided by doubling the material at its exposed edges and stitching flat the overlapping portions. A braid or tape 11^a is secured about the three unattached edges of flap 11. 55

As previously indicated, flap 11 is more readily manufactured separately from the body of the garment and subsequently attaching it thereto, such technique facilitating the attachment of lining material 15 and the formation of the pockets 17 and 18 in the manner herein indicated. When so made, the flap 11 is secured to back 10 by 60 stitching 21, and such stitching may be passed through the lining material 15 in order to securely affix it in position. 65

For closing flap 11 over front sections 12 and 13 of the garment, a plurality of registering buttons 22 and buttonholes 23 are arranged upon said parts as is best shown in Figures 1 and 2. The flaps 20 may be adapted to close pockets 17 and 18, by the use of buttons and buttonholes, or any other conventional fastening device, such as a snap fastener. 70 75

Pockets 17 and 18 are adapted to provide storage spaces for various articles, particularly additional articles of the child's apparel. Waterproofed as these pockets are, no damage to the fabric of the coat may result from the carrying of wet or soiled articles, and fresh articles may be kept separate from those which have been used. 80 85 Great convenience is had from providing a carrying device attached and arranged in the manner described.

Flap 11 also provides extra thicknesses of material about the child's feet, thus supplying additional warmth and preventing exposure even should the child's feet slip through the coat front. 90

We claim:

A baby's coat comprising a back, a front having sides adapted to fasten upon the adjacent edges thereof, a flap upon said back depending below said front and adapted to be folded thereover and button to said sides to close the bottom of said coat, and buttons upon said sides, said flap including a sheet of waterproof material disposed upon the 95 100

inside of said flap in layers and having an extension depending below said flap upon said back, the layers of said waterproof sheet being fastened one to another to provide a plurality of pockets coextensive with said flap and adapted to be closed by said extension, said pockets opening from the bottom

of said flap when said flap is in extended position, said buttons for securing said flap to the front of said coat passing through 10 said waterproof material and said extension to more securely close said pockets.

JACOB GREENBERG.
SAMUEL GOODMAN.
